UNITED STATES PATENT OFFICE.

SIMON COOPER, OF BROOKLYN, NEW YORK.

PACKAGING MACHINE.

Application filed March 22, 1921, Serial No. 454,429. Renewed October 9, 1926.

This invention relates to the manufacture of wrappers or packages and the objects of the invention are to provide a relatively simple and practical machine, which will automatically and expeditiously make up the wrappers in the desired form.

The invention involves a number of novel features of construction, combinations and arrangements of parts, as will be disclosed in the following specification, which is to be read in conjunction with the accompanying drawings wherein I have illustrated a practical commercial embodiment of the invention.

15 In the drawings referred to,

Figure 1 is a broken side elevation, and

Figure 2 is a top plan view of the machine, these views being more or less diagrammatic for the purpose of better illustrating the sequence of operations.

Figure 3 is an enlarged and part sectional view of the front or paper-feed end of the machine.

Figure 4 is a broken side view of this end portion of the machine.

Figure 5 is a broken detail side view of the top flap gluing devices.

Figure 6 is an end view of the same taken transversely of the machine.

30 Figure 7 is a broken detail view of the mechanism for "heeling" in the rearward edge at the upper end of the wrapper, this view being taken transversely of the machine.

Figure 8 is a side view of these same parts.

Figures 9 and 10 are end and side views respectively of the mechanism for folding in the forward edge of the wrapper.

Figure 11 is a detail plan view of the presser for the seam of the wrapper.

Figure 12 is a plan view of the same and in addition, the first heeling in or end tucking mechanism.

Figure 13 is a transverse sectional view of the machine at the plane of the side seam presser.

Figure 14 is a diagrammatic plan view of the side seam folding devices.

50 Figure 15 is a view partly diagrammatic, illustrating the operation of feeding the paper, cutting the same at the proper length for a wrapper and shaping the severed portion about the mandrel.

Figure 16 is a detail plan view of the paper cutter.

Figure 17 is a broken plan view of the mechanism for holding and "breaking" the wrapper about the mandrel.

Figure 18 is a broken plan view of the side seam folding devices. 60

Figure 19 is a side view of the same taken transversely of the machine and illustrating diagrammatically the relation of the paper feeding and cutting mechanism thereto.

Figures 20 to 27 are detail views, illustrating successive operations in the formation of the wrapper or package. 65

Figures 28 and 29 are broken plan and side views of the tuck spreading device.

Figures 30 and 31 are detail edge and side views of one of the mandrels. 70

In accordance with my invention the paper or wrapper forming material is automatically advanced and held against a mandrel while it is being cut to the proper length (Figure 15). During the feeding operation, glue or other adhesive is applied near one edge of the wrapper. After severance from the main body of the paper, a presser breaks the wrapper about the sides of the mandrel and while thus held, the edges of the wrapper are folded one over the other producing overlapping flaps which are secured together by the previously applied adhesive (Figures 20 to 23). The mandrel with the wrapper thus secured in the form of a tube thereon, is then advanced from the flap folders (Figure 14) past a pressure plate which holds the side seam while the adhesive is "setting" (Figure 12). 90

From the presser the mandrel is advanced to carry the upper end of the wrapper beneath a tucking device which at such time is operated to heel in the rearward upper edge of the wrapper (Figures 7, 8 and 24). 95 In the next advancing movement of the mandrel, the forward upper edge is carried beneath a plow (Figures 9 and 10) which tucks in the forward upper edge of the wrapper (Figure 25).

100 In the next advancing movement, the pointed flaps at the upper end of the wrapper are spread apart (Figure 28) and at the next movement, one of these flaps passes beneath a glue-applying device. On the succeeding movement, the adhesive flap is turned down over the end of the wrapper and on the following movement, the other flap is treated with adhesive and turned down over the first secured flap. The wrap- 110

pers thus finished may be then automatically ejected from the mandrels or in some instances, cartons may be slipped over the wrappers while still on the mandrels.

5 With this general operation in mind I will now describe the parts in detail.

The paper-feeding mechanism at the front end of the machine is supported in the upright side frames 1 and 2 (Figures 3 and 4) 10 carried by the longitudinal side sills 3 and 4 which form the base of the machine. The side frames 1 and 2 carry at their upper extremities, the rolls 5 supporting the paper roll 6.

15 The web of paper is advanced by means of the paper-feeding rolls 7 and 8, between which the web is passed, as indicated in Figure 15. These paper-feeding rolls are intermittently operated by suitable gearing, a 20 portion of the connecting gearing between said rolls being indicated at 9 and 10 in Figure 4. I have also shown in this view and in Figure 3 how the outer paper-feeding roll 8 may be journaled in brackets 11 fixed 25 on the supporting shaft 12 which is provided with handles 13 by which said shaft can be rocked for the purpose of shifting the roll 8 toward or away from the companion feeding roll 7.

30 The gluing mechanism for the side seam is illustrated in Figures 3 and 4 as consisting of a glue box 15 pivoted at one end at 16 and adapted to be raised and lowered by means of a link 17 pivoted to its free end 35 and acted on by a cam 18 on the longitudinally extending shaft 19. In the forward end of this glue box there is journaled a glue roll 20 carrying a gear to mesh with the constantly rotating gear 95 when the box 40 is raised. Backing rollers 21 support the paper while the glue roll 20 is applying the strip of adhesive to the face thereof (Figure 15).

The glue-applying roll is positioned to apply 45 a strip of the adhesive adjacent one longitudinal edge of the paper (the near edge in Figure 3) as is timed to terminate this strip at a point short of what becomes the upper edge of the wrapper. This strip 50 of adhesive is indicated at 20^a in Figures 21 and 22. The feed roller 7 may be relieved or cut away at a point in line with the adhesive strip, as indicated at 20^b in Figure 2.

The cooperating feed rolls 7 and 8 advance 55 the forward end of the paper into position in front of one of the mandrels or formers 44, as indicated at 6^a in Figure 3, and after the paper is gripped against the mandrel, the cutter blade 22 is operated to sever the wrapper-length of paper. This paper cutter is 60 supported from the side frame by the bracket 23 and includes a fixed blade 24 which cooperates with the movable blade 22.

The movable cutter blade is actuated at 65 the proper time from a link 96 (Figure 4)

which is actuated by a cam 97 on cam shaft 19 and is connected with a rocker arm 98 carrying an upwardly projecting arm 99 connected by a strap 99^a with a rearwardly projected portion of the cutter blade at 70 25 (see also Figure 16).

The wrapper-length of paper is first gripped and held against the mandrel 44 by a presser, illustrated at 34 in Figures 15 and 17 and shown as carried by a spring-pressed 75 plunger 35 operating in the carrier 36. This carrier is formed with bearings 37 sliding on the supporting rods 27 and is reciprocated back and forth by a link 28 connected with the upstanding arm of a bell-crank 29 pivoted at 30 and carrying on its other arm a roll 31 cooperating with the cam 32 on cam shaft 19. At the opposite sides of the clamping plate 34 are the presser plates 33 pivoted on the carrier 36 by means of spring hinges 33^a. 85

In the forward movement of the carrier 36, the presser head 34 first engages the dependent portion of the paper and clamps the same against the rearward face of the mandrel 44. When thus held, the knife operates 90 to sever the wrapper from the end of the web of paper. In the continued forward movement of the carrier 36, the presser plates 33 operate to bend the protruding wings of the paper about the rearward corners of the mandrel, as indicated in Figure 21.

95 After this the flap folder 45 (Figures 1, 2 and 14) is swung inwardly to fold the edge of paper which has been glued, over the front of the mandrel and then the second flap folder 46 is swung inward to fold the second flap over the adhesive portion of the second flap (Figures 22 and 23). The construction of these flap folders is shown in 100 Figures 18 and 19. In these views, 47 indicates a cam provided on the cam shaft 19 and arranged to operate the folders through the medium of a rod 48 carrying a roll 49 at one end engaging the cam, and a rack 110 50 at its other or outer end engaging a pinion 51 on the lower end of the upright shaft 52.

This upright shaft carries the outstanding 115 tubular arms 53 in which are slidably received the arms 54 of the folding blade or roll 46. The folding roll is pressed outwardly by means of springs 55 surrounding the portions 54 which telescopically fit in the tubular arms 53, the outward movement 120 of the folding roll being limited by nuts 56 engaged on the rearward or shaft ends of the arms 54.

The first folding device is operated from 125 the second folding device by means of an outstanding arm 57 on the shaft 52 engaging a lug or shoulder 58 on the arm 59 which is secured to the lower end of the upright supporting shaft 60. This shaft, like the shaft 52, carries outstanding tubular arms 130

61 slidingly receiving the rods or arms 62 of the folder 45, springs 63 being provided for forcing said arms outwardly in their tubular bearings, such movement being limited by stop nuts 64 on the extended inner ends of rods 62. The folder 45 is shown as provided with angularly projecting shoes or folder blades 67 for sliding contact with the wrapper, these blades being tensioned 10 against the wrapper through the medium of an outstanding arm 65 connected with the folding roll 45 and engaged by a tension spring 66.

The parts described are so timed and related that as the rack 50 moves inwardly under the action of cam 47, and the shaft 52 is thereby rotated in the left hand direction in Figure 18, the arm 57 will swing away from the lug 58 and thereby permit the tension spring 68 connected with the lever 59 to swing the first folding roll 45 toward the lower edge of the wrapper. As this first folder moves into engagement with the projecting edge of the wrapper, the shoes 67 20 break the wrapper around the corner of the mandrel and hold it in this position while the second folder in its continued movement, engages and breaks the other edge of the wrapper about the upper right hand corner 30 of the mandrel, the final position of the two folders being substantially as indicated in Figure 14.

The mechanisms thus far described in detail are all located at what may be considered the first station of the machine (see Figure 2). Thus, at this first station, the paper is fed, adhesive is applied adjacent one edge, to a wrapper-length of the paper, the dependent portion of a wrapper-length is 40 clamped against the adjacent face of a mandrel, the wrapper is then severed from the balance of the strip, the edges of the wrapper are broken about the sides of the mandrel and are then folded together into overlapping relation over the front face of the mandrel. The feed roll is recessed in line with the adhesive strip to prevent gumming the same, and the adhesive-applying operation is discontinued in time to leave a blank 50 space at the end of the wrapper in line with the cutter, so that gumming of the cutter is also avoided.

The mandrels 44 are shown as mounted equidistantly on plates 43 carried by a continuous belt or conveyor 38, said plates 43 sliding in guide-ways 43^a and being held rigidly in upstanding relation by the angle braces 45. The endless belt or chain 38 is supported at the rear end of the machine by 60 a pulley or sprocket 39 on shaft 40 and at the front end of the machine, said belt or chain is supported by the pulley 41 on shaft 42, one or both of said shafts being driven to give the necessary intermittent motion to the 65 conveyor.

At station 2, (Figure 2) there is provided a presser 68 for holding the overlapped seam while the adhesive is setting. This presser as shown in detail in Figures 11, 12 and 13, is usually constructed as a smooth plate having the forward edge thereof relieved or turned outwardly and as supported by brackets 70 on the rods 69 slidingly fitting in said brackets and operated on by springs 71. 70

After the primary folders 45, 46 complete 75 the side seam, as in Figure 14, said folders momentarily rest in this position while the mandrel advances to the second station, thereby causing the seam just completed to be wiped by folder 46. This gives a preliminary set to the seam which is completed and made secure by the presser 68. 80

At station 3 there is provided a tucker 72 carried by rock shaft 73 journaled in a bearing 74 and operated by a rock arm 75 to which there is connected a link 76 actuated by cam 77 on cam shaft 19, link 76 carrying a yoke 78 at its lower end bearing a roll 79 in engagement with said cam (Figures 7 and 8). 85

When the wrapper is advanced to station 3, the tucker 72 occupies the dotted position shown in Figure 8 and is then rocked downwardly to heel in the rearward upstanding edge of the wrapper 2 as indicated at 72^a in 90 Figure 24.

In its passage to station 4, the wrapper passes beneath a plow or folding plate 79 supported by pins 80 slidingly fitting in the stationary supporting bracket 74, said plate 100 operating to tuck in the forward upper edge of the wrapper tube, as indicated at 79^a in Figure 25.

At or adjacent station 4, there is provided an opener 81 having a tapered nose 81^a to 105 enter between the upstanding pointed flaps of the wrapper tube and to spread them apart in flat relation, as indicated at 81^b in Figures 28 and 29.

The wrapper has thus advanced to station 5 with the pointed flaps or ears outstanding or projecting laterally from the upper end of the wrapper and at this station one of the flaps, the lower one in Figure 2, is engaged by a double glue roll 83 rotating transversely to the advancing movement of the carrier and adapted to apply two spots or strips of adhesive to this one flap. 110

The construction of this adhesive-applying mechanism is illustrated particularly in 120 Figures 5 and 6, and as there shown, the double roll 83 operates partly in the glue box 84 carried by a bracket 89 which is pivoted at 90 and is rocked downwardly at the proper instant by a push rod 91 having a fork 92 at its lower end carrying a roll 93 in engagement with a cam 94 on the cam shaft 19. 125

In the passage of the wrapper from station 5 to station 6, the adhesive flap is turned 130

over and pressed down on top of the wrapper in the manner indicated in Figure 26 by a turn-down folder 82 (Figures 1 and 2).

In the passage from station 6 to station 7, the second flap passes beneath the glue-applying roll or rolls 85 (Figures 1, 2 and 5) which rotate in the plane of the second flap and travel in the same direction and at the same linear movement as the wrapper so as to apply a strip or strips of adhesive from the glue box 86 to the upper surface of the second flap. As the wrapper approaches station 7, the second flap with the adhesive thereon is turned over by the folder blade 87 and pressed down over the first flap, thus sealing the upper end of the box or package. This final folder 87 may be extended for some distance, as indicated in Figure 1, to hold the flaps until the adhesive has thoroughly set.

After the wrappers have thus been formed on the mandrels, various other operations may be carried out while said wrappers are still on the mandrels. Thus, the conveyor may be extended and means may be provided for automatically slipping cartons over the wrappers. This work also may be done by hand at a station provided for this purpose.

30 The wrappers and also the cartons, if cartons have been placed over the wrappers, may be held on the mandrels after the conveyor has passed over the pulley at the end of the machine, by a supporting roll provided for that purpose and, if desired, means may be provided for automatically ejecting the wrappers or both wrappers and cartons when a predetermined point is reached in the travel of the conveyor.

40 A suitable form of ejector is illustrated particularly in Figures 30 and 31 where 88 designates a slide or pusher at the end of the mandrel which is adapted to be actuated by an outstanding pin 100 disposed near the inner end of the mandrel and projecting through a slot 101 in the face of the mandrel into position to engage a cam track or roll standing at the side of the conveyor.

It will be understood that suitable mechanical connections will be provided between the various elements illustrated, to produce the proper sequence of operations as described. I have illustrated certain of these connections in a conventional way, but 55 wish it understood that any desired mechanisms of this character may be employed.

It will be understood also that the structure may be modified to suit various requirements encountered in the art, and this without departing from the scope of protection herein claimed. It will also be understood that the terms which I have employed are in a descriptive rather than in a limiting sense, except for such limitations as may be imposed by the condition of the art.

What I claim is:

1. In a machine of the character described, a traveling mandrel, means for advancing a web of material into position at the side of said mandrel, means for clamping said material against the mandrel, means for severing the material while thus held and means for folding the severed length of material about the mandrel. 70

2. In a machine of the character described, a former, means for feeding a strip of material into position adjacent said former, means for applying adhesive to a pre-determined length of said strip during the feeding movement thereof, means for clamping said strip against the former, means for severing the strip adjacent the former while clamped thereto and means for folding said severed length with the adhesive material about the former. 75 30 85

3. In a machine of the character described, a mandrel, means for feeding a length of material in position beside the mandrel, means for holding the thus fed length of material against the mandrel, means for applying adhesive to said length of material during the feeding movement thereof and arranged to leave a portion of the material bare, means for severing the length of material at the bared portion 90 95 thereof and folding devices for folding the severed length of material about the mandrel.

4. In apparatus of the character described, a mandrel, an adhesive-applying device, means for feeding a sheet of material past said adhesive-applying device to the mandrel, means for engaging the adhesive-applying device with the sheet during the feeding motion thereof and for withdrawing the adhesive-applying device from the sheet to leave a portion of the sheet bare of adhesive, means for severing the sheet at such bare portion, means for folding the severed sheet about the mandrel and means for applying adhesive to the bare portion of the sheet on the mandrel. 100 105 110

5. In apparatus of the character described, a mandrel, an adhesive-applying device, means for feeding a sheet of material past said adhesive-applying device to the mandrel, means for engaging the adhesive-applying device with the sheet during the feeding motion thereof and for withdrawing the adhesive-applying device from the sheet prior to the end of the feeding movement to leave a portion of the sheet bare of adhesive, means for severing the sheet at such bare portion, means for applying adhesive to the bare portion of the sheet on the mandrel and means for then folding said last portion to which the adhesive has been applied. 115 120 125

6. In combination, a mandrel, a cutter above said mandrel, means for feeding a web 130

of material down past said cutter into position at the side of the mandrel, means for holding the dependent section of the material against the mandrel and means for then operating the cutter to sever said held section from the balance of the material.

7. In combination, a mandrel, a cutter above said mandrel, means for feeding a web of material down past said cutter into position at the side of the mandrel, means for holding the dependent section of the material against the mandrel, means for then operating the cutter to sever said held section from the balance of the material and folding devices for then shaping the severed and held section of material about the mandrel.

8. In combination, a mandrel, a cutter above said mandrel, means for feeding a web of material down past said cutter into position at the side of the mandrel, means for holding the dependent section of the material against the mandrel, means for then operating the cutter to sever said held section from the balance of the material and means for applying adhesive to the material on its passage to the cutter and for terminating said adhesive at that portion of the material which is operated on by the cutter.

9. In combination, web feeding devices, means for operating the same to advance a predetermined length of material, an adhesive-applying device, means for operating the same to apply adhesive to a portion only of the length of material during the advancement of the web by the web feeding devices and a severing device positioned to operate on a portion of the material which is bare of adhesive.

10. In a machine of the character described, means for supporting a web of paper, an adhesive-applying device, means for feeding a length of the web with a portion thereof in contact with said adhesive-applying device, means for severing a length of the web to which adhesive has been applied, a mandrel positioned below said severing means and folding devices arranged to fold the severed length about said mandrel.

11. In a machine of the character described, a mandrel traveling in a definite path, means for applying a tubular wrapper thereto, an adhesive-applying device operating transversely of the mandrel travel and a second adhesive-applying device operating longitudinally of the mandrel travel.

12. In a machine of the character described, a mandrel traveling in a definite path, means for applying a tubular wrapper thereto, an adhesive-applying device operating transversely of the mandrel travel, a second adhesive-applying device operating longitudinally of the mandrel travel and means for positioning portions of the wrapper on

the mandrel in place to be acted on by said adhesive-applying devices.

13. In a machine of the character described, a mandrel traveling in a definite path, means for applying a tubular wrapper thereto, an adhesive-applying roll operating transversely of the mandrel travel and a second adhesive-applying roll operating longitudinally of the mandrel travel.

14. In combination, a longitudinally traveling mandrel, a transversely rotating glue roll for applying adhesive to a wrapper on the mandrel and a longitudinally rotating glue roll for applying adhesive to the wrapper.

15. In combination, a traveling mandrel for supporting a wrapper, an adhesive-applying device in the path of the wrapper on said mandrel and operating transversely of the mandrel travel and means for intermittently oscillating said device to carry the same into engagement with the wrapper on the mandrel.

16. In combination, a traveling mandrel for supporting a wrapper, an adhesive-applying device in the path of the wrapper on said mandrel and operating transversely of the mandrel travel, means for intermittently oscillating said device to carry the same into engagement with the wrapper on the mandrel and a second adhesive-applying device operating in the line of travel and at the same speed of movement as the wrapper on the mandrel.

17. In combination, a series of spaced traveling mandrels, a plunger associated with each of said mandrels, means for forming wrappers about said mandrels, and means for automatically actuating the plungers for discharging said wrappers from the mandrels at a predetermined point in the travel of the same.

18. In a machine of the character described, a forming mandrel, a sliding ejector mounted therein and an operating pin projecting from said ejector.

19. In a machine of the character described, a mandrel and a swinging resilient folder for folding the edge of a wrapper over said mandrel, said folder having angularly projecting spring operated shoes for contact with the wrapper.

20. In a machine of the character described, an oscillating shaft, an outstanding spring pressed folding element carried by said shaft, a second oscillating shaft, an outstanding spring pressed folding element carried by said second shaft and connections between said shafts for causing one to follow the operation of the other.

21. In a machine for making boxes of the character described, the combination of intermittently moving vertical mandrels, means for positioning a length of paper at one of the vertical sides of said mandrel,

a device for clamping said length against the mandrel and means for then severing said clamped length at a predetermined point.

5 22. In a machine for making boxes of the character described, the combination of intermittently moving vertical mandrels, means for positioning a length of paper at one of the vertical sides of said mandrel, a 10 device for clamping said length against the mandrel, means for then severing said clamped length at a predetermined point above the upper end of the mandrel and means for shaping said severed length in

15 tubular form about the mandrel and for turning in the projecting upper portion of the same.

23. In a machine for making paper boxes, an intermittently moving vertical 20 mandrel, means for forming a tubular wrapping about said mandrel, means for heeling in oppositely disposed portions at the upper end of the wrapper, means for forcing outwardly flaps of the wrapper between 25 said heeled in portions and means for applying two narrow strips of adhesive to one of said outstanding flaps.

24. In a machine for making paper boxes, an intermittently moving vertical mandrel, 30 means for forming a tubular wrapping about said mandrel, means for heeling in oppositely disposed portions at the upper end of the wrapper, means for forcing outwardly flaps of the wrapper between 35 said heeled in portions, means for applying two narrow strips of adhesive to one of said outstanding flaps, means for folding in said adhesive flap and devices for applying adhesive to the other flap and for folding the 40 same over the first flap.

25. In a machine for making paper boxes, an endless conveyor having upper and lower reaches, mandrels projecting from said conveyor, a plunger associated 45 with each mandrel box-forming mechanism

co-operating with the mandrels on the upper reach of the conveyor and means along the lower reach of the conveyor for actuating the plungers for ejecting the boxes from the mandrels.

50

26. In a machine for making paper boxes, means for separately and successively applying adhesive to two outside top flaps of a wrapper, means for folding one of said flaps before the adhesive is applied 55 to the other flap, and means for folding the last mentioned flap over the folded flap and for maintaining pressure on the flaps after such folding.

27. In a machine for making paper 60 boxes, a mandrel, a folder for bending the edge of a wrapper over said mandrel, means for applying adhesive to said edge, a second folder for laying another fold of the paper over said first fold and in contact 65 with the adhesive, means for operating the first folder to hold the first fold while the second folder is operating, means for shifting the mandrel past the folders and means for holding the second folder relatively stationary during such advancing movement to thereby cause the same to wipe the seam produced.

28. In a machine for making paper 70 boxes, means for separately and successively folding the top flaps of a wrapper one over the other and means for applying adhesive to the flaps just prior to each of said folding operations.

29. In a machine of the character described, a former, coacting rolls for feeding a sheet of material into position adjacent the former, means for applying a strip of adhesive to a predetermined portion of said sheet, one of said feed rolls being circumferentially grooved in alignment with the adhesive strip.

In testimony whereof I affix my signature.

SIMON COOPER.
